UNITED STATES PATENT OFFICE.

FRANK L. NAU AND HARRY D. NAU, OF CROOKSTON, MINNESOTA.

POTATO-HILLER.

1,296,840.

Specification of Letters Patent. Patented Mar. 11, 1919.

Application filed November 30, 1917. Serial No. 204,733.

To all whom it may concern:

Be it known that I, FRANK L. NAU and HARRY D. NAU, citizens of the United States, residing at Crookston, in the county 5 of Polk and State of Minnesota, have invented certain new and useful Improvements in Potato-Hillers, of which the following is a specification.

Our invention relates to hillers, which 10 may be adapted to any pulling power for the purpose of drawing the hillier longitudinally of a row of plants, for piling dirt up around the plants.

An important object of our invention is 15 to provide a device of the above mentioned character including means whereby various heights of earth may be piled up around plants.

Another object of our invention is to provide a device of the above mentioned character including means whereby piles of earth 20 of various widths may be piled up around plants.

Another object of our invention is to provide a device of the above mentioned character which is strong, durable, inexpensive 25 to manufacture and efficient in practice.

Other objects and advantages will be apparent during the course of the following 30 description.

In the accompanying drawings forming a part of the description and wherein like numerals are employed to designate like parts throughout the same,

35 Figure 1 is a side elevation of our invention, the dotted lines showing the adjustment made for a higher hill of earth.

Fig. 2 is a front view of our invention, and

40 Fig. 3 is a sectional view of the same taken on the line 3—3 of Fig. 1.

In the accompanying drawings wherein is shown a preferred embodiment of our invention, the numeral 1 designates an arch 45 structure, which is circular in cross section, and has its free ends oppositely disposed at right angles to the arch, as at 2, then inclined slightly downward to form the axle sections 3. Harrow disks 4 are adjustably 50 mounted upon the incline axle sections and are clamped in any desired position by the slideable collars 5, carrying the usual set of screws, and are adapted to be mounted upon the incline axle sections and clamp against 55 the opposite faces of the harrow disks.

The hillier is drawn by means of a pair of elongated rods 6, carrying an opening at each end thereof. These rods extend forwardly of the hillier and have the rear ends received on the angular portion 2 of the arch 60 and held in position by the collars 7, which are similar to the collars 5. The opening 8 in the forward end of the drawing rods 6, is for the reception of a bolt to secure the hillier to the drawing power. A pair of 65 bars 9, each of which is provided with a longitudinal slot 10, are adapted to be pivotally connected at the lower ends with the drawing rods 6, at a point intermediate the ends of the rods 6, by means of bolts 11. 70 These bars 9 are arranged at an angle to the arch and drawing rods, and are adapted to be adjustably connected to the arch, by means of the bolts 12 passing through the arms of the arch, adapted to operate in the 75 slots 10. Nuts are secured on the outer threaded end of the bolts 12, and washers are interposed between the bars 9 and the arms of the arch. The brace rods 13 are pivotally connected to the drawing rods 6 80 by means of the bolts 11, and extend forwardly at an angle to the drawing rods 6 to be attached to the drawing power. These brace rods are adapted to be secured to the drawing power by the openings 14 in the 85 forward ends thereof, co-acting with bolts adapted to pass through these openings, and through openings in the frame of the drawing power.

The hillier is adapted to straddle the row 90 of vegetation and to be drawn longitudinally thereof by any suitable power. As the hillier moves along the row, the harrow disks plow up the earth which is guided off of the disks by means of the angular arrangement upon the axle sections, as more clearly shown in Fig. 2.

Various heights of hills will be thrown up by simply loosening the nuts on the bolts 12 and swinging the arch either forward or 100 backward. It will be seen that by arranging the bars 9 at an angle to the arch and rods 6 it requires comparatively no exertion to make the angular adjustments of the arch. Various widths of hills may be 105 thrown up by adjusting the disks along the inclined axle sections.

It is to be understood that the form of our invention herewith shown and described is to be taken as a preferred example of the 110

same, and that various changes in the shape, size, and arrangement of parts may be resorted to without departing from the spirit of the invention or the scope of the subjoined claims.

Having described our invention we claim:

1. A potato hillier including an arch, axle sections arranged at an angle to said arch, disks adjustably mounted thereon, means for drawing the hillier, and slotted rods connected to the arch and drawing means for adjusting the angle of the arch.

2. A potato hillier including an arch, axle sections arranged at an angle thereto, disks adjustably mounted on said axle sections, means for drawing the hillier, slotted rods connected to the arch and drawing means at an angle, and means arranged upon the arch to coöperate with the slotted bar for holding the arch at various angles.

3. A potato hillier including an arch, disks carried by said arch, drawing rods connected to said arch, and rods pivoted to said

drawing rod and adjustably connected to said arch.

4. A potato hillier including an arch, disks carried by said arch, drawing rods connected to said arch, rods pivoted to said drawing rods, and adjustably connected to said arch, and brace rods pivotally secured to the said drawing rods.

5. A potato hillier including an arch having its free ends bent outwardly thereof in opposite directions then downwardly to provide axle sections, disks adjustably mounted upon said axle sections, means for drawing the hillier, and slotted rods connected to the arch and drawing means for adjusting the angle of the arch and the axle sections.

In testimony whereof we affix our signatures in presence of two witnesses.

FRANK L. NAU.
HARRY D. NAU.
